UNITED STATES PATENT OFFICE.

PAUL CONCIENNE, OF BELLE ROSE, LOUISIANA.

PROGRAM CLOCK.

Application filed December 30, 1922. Serial No. 610,070.

To all whom it may concern:

Be it known that I, PAUL CONCIENNE, a citizen of the United States, residing at Belle Rose, in the parish of Assumption and State of Louisiana, have invented new and useful Improvements in Program Clocks, of which the following is a specification.

This invention relates to time controlled signal devices and has for its object the provision of a novel electrically operated signal device associated with a clock whereby to ring any number of bells in accordance with the program in schools, colleges and other places where such an arrangement is desirable.

An important object is the provision of a system of this character which may be used in conjunction with a common ordinary clock, the essential elements of my device being capable of use as an attachment and being engageable upon a clock in a very simple manner which will involve little expense in manufacture and installation of the system.

Another object is the provision of an apparatus of this character which is provided with a circuit control means whereby any desired number of bells may be plugged in or cut out of the circuit to meet various conditions.

With the above and other objects and advantages in view the invention consists in the details of construction to be hereinafter more fully described and claimed and illustrated in the accompanying drawings, in which:

Figure 1 is a face view of a clock equipped with my circuit closers,

Figure 2 is an enlarged elevation of a fragment of the dial showing the contact members traveled over by the minute hand,

Figure 3 is a view similar to Figure 2 showing the contact members traveled over by the hour hand,

Figure 4 is a detail section taken across Figure 2 on the line 4-4,

Figure 5 is a similar section taken across Figure 3 on the line 5-5,

Figure 6 is a section on the line 6-6 of Figure 2,

Figure 7 is a detail view showing the roller on the minute hand.

Referring more particularly to the drawings the letter A designates an ordinary clock including a dial B surrounded by a

metal rim C, while D and E represent the minute and hour hand respectively.

In carrying out my invention I provide a series of metal contacts 10 which are preferably soldered or otherwise secured to the rim C and which extend inwardly thereof. An alternative arrangement is that the paper or enamel face of the dial be scraped or otherwise treated to leave bare spaces. The contacts 10 are intended to be mounted at regular intervals, say for instance five minutes apart, that is to say thirty degrees apart.

The minute hand of course co-operates with these contacts 10 and secured upon the end thereof is a wire or arm 11 upon the free end of which is journaled a roller 12 which will engage the successive contacts 10 as the hand moves during the running of the clock.

The hour hand E carries a similar arm or wire 13 upon which is journaled a roller 14. Secured upon the face of the clock in the path of the hour hand is a ring 15 of insulating material which is preferably dove tailed in cross section and adjacent which is mounted a metallic ring 16. Detachably engaged upon the ring 15 is a plurality of clips 17 constructed of metal and of such formation as to snap onto the ring 15 and be retained thereon owing to the peculiar shape thereof. The inside edge of each clip is formed with a tongue 18 which may be engaged by the fingers or by some implement such as a screw driver or the like when it is desired to remove the clip from its normal position.

When these clips are in position they are ordinarily out of engagement with the metal ring 16 and when any clip is needed to operate, the connection is effected by a V-shaped expandible connector clip 19 which is engaged beneath the tongue 18 in contact with the ring 16. The clips or contact members 17 are arranged at such intervals as desired to correspond to the intervals between the contacts 10. For a five minute interval, twelve clips are required to be inserted in the space traveled over by the hour hand during one hour so that when the roller carried by the minute hand is in engagement with the proper one of the contacts 10 the roller carried by the hour hand will be in engagement with the proper one of the contact clips 17.

In connection with the above described

clock arrangement, it is of course necessary to provide a battery 20 or other suitable source of current which has one terminal connected with the rim C and which 5 has its other terminal connected with one terminal of a bell 21, it being of course understood that any desired number of bells may be used connected in parallel. Leading 10 from the other terminal of the bell is a wire 22 which is connected with the metal ring 16. In the operation it is of course apparent that when the connector clips 19 are in place associated with the proper one or ones of the clips 17, and when during 15 the running of the clock the hour hand reaches these connected clips 17 with the minute hand roller engaging the successive contacts 10, the circuit will be closed through the bell or bells for energizing them and 20 giving the desired signal.

From the foregoing description and a study of the drawings it will be apparent that I have thus provided a simply constructed and easily installed arrangement 25 or attachment by means of which an ordinary clock may be converted into an automatic electric signalling device for controlling bells or other similar devices for indicating the different periods of lectures, 30 classes, etc., in schools, colleges and other institutions.

While I have shown and described the preferred embodiment of the invention it is of course to be understood that I reserve the 35 right to make such changes in the form, construction and arrangement of parts as will not depart from the spirit of the invention or the scope of the subjoined claims.

Having thus described my invention I 40 claim:

1. A circuit making attachment for clocks consisting of a plurality of contacts electrically connected with the metallic rim of the clock face and co-operating with a roller

carried by the minute hand, a supporting ring of insulating material carried by the clock face, a plurality of contact clips engaged upon said last named ring and located in the path of travel of the hour hand, a metallic ring mounted upon the clock face adjacent said ring of insulating material, said contact clips being normally spaced from said last named metallic ring, and means for selectively connecting the contact clips with the last named metallic ring. 45

2. A circuit making attachment for clocks consisting of a plurality of contacts electrically connected with the metallic rim of the clock face and co-operating with a roller carried by the minute hand, a supporting ring of insulating material carried by the clock face, a plurality of contact clips detachably engaged upon said last named ring and spaced apart in the path of travel of 50 a roller carried by the hour hand, a metallic ring mounted upon the clock face adjacent said ring of insulating material, said clips being normally spaced from said last named metallic ring, and means for selectively connecting the clips with the last named metallic ring, said means consisting of expandable connector clips insertable between said last named metallic ring and tongues on said clips. 55

3. In a program clock, a ring of insulating material mounted upon the face thereof, a plurality of contact clips engaged upon said ring and formed with elongated tongues, a metallic member adjacent the ring of insulating material, and V-shaped expandable 60 connector clips insertable between said metallic member and said tongue for effecting electrical connection of the contact clips with the metallic member. 75

In testimony whereof I affix my signature:

PAUL CONCIENNE.
